UNITED STATES PATENT OFFICE.

WILLIAM M. HALLBAUER, OF ST. LOUIS, MISSOURI.

VALVE-SPRING LIFTER.

1,064,640.

Specification of Letters Patent. Patented June 10, 1913.

Application filed May 8, 1911. Serial No. 625,935.

To all whom it may concern:

Be it known that I, WILLIAM M. HALLBAUER, a citizen of the United States, residing at St. Louis, State of Missouri, have 5 invented certain new and useful Improvements in Valve-Spring Lifters, of which the following is a specification.

My invention relates to tools for compressing the springs on the stems of valves to 10 permit a retaining nut or cross pin to be attached to the stem, and has for its object the provision of a device having an adjustable pin to engage the valve piston, a slotted lifter arm to receive the stem of the 15 valve, a circular socket to receive the lower end of the valve spring, and a cam lever for actuating the lifter arm, the whole combining to comprise a very efficient tool that is simple in construction and easy to operate. 20 My invention will be described in detail hereinafter and illustrated in the accompanying drawings in which—

Figure 1 is a side view of the tool with the operating cam lever shown in an inoperative position, Fig. 2, a top plan view, 25 Fig. 3, a view similar to Fig. 1 showing the cam lever in operative position applied to a valve, and Fig. 4, a sectional detail of the spring engaging arm.

30 In the drawings similar reference characters will be used to designate corresponding parts in the several views.

The frame 1 of my improved valve spring lifter is formed of a bar T-shaped in cross 35 section, and consisting of an upright portion 2, having arms 3 and 4 on its upper and lower ends respectively. Arm 3 has its free end bifurcated as shown at 3^a, while arm 4 is provided with an open slot 4^a and 40 a circular recess 5 in its upper face.

6 indicates a plate provided with a plate 6^a upon its lower surface, and also provided with a notch 7 in one end to engage the upright 2 and is slidably mounted thereon.

45 8 indicates a screw threaded pin secured to the underside of plate 6^a, and 9 an inferiorly threaded adjusting thimble mount-

ed on pin 8 and having its lower end tapered as shown at 10.

11 indicates a lever fulcrumed in the bifurcated end of arm 3 and having a cam face 12 and stop 13 that engages the upper side of plate 6 when in operation.

My device is adapted to be applied to a valve structure A as shown in Fig. 3. The 55 thimble 9 engages the disk B, the plate 6 engages the top of the casing and the plate 6^a fits within the opening D in the valve casing and centers the device. The valve rod C extends through the opening 4^a in the 60 arm 4 and the spring E is seated in the recess 5. When the cam lever is thrown from the position shown in Fig. 1 into the position shown in Fig. 3 the frame of the device is raised relatively to the plate 6, and it is 65 obvious that the spring will be compressed so that the spring retaining nut or cross-pin may be readily attached to or detached from the valve rod.

Having thus described my invention what 70 I claim is—

1. In a valve spring lifter, a U shaped frame, a cam lever fulcrumed upon one arm of said U, a plate slidably mounted on said frame and engageable by said cam, the other arm of said U being provided with a slot for the reception of a valve rod and a recess for seating a valve spring, and a pin on said 75 slideable plate adapted to engage said valve rod.

2. In a device of the character described, an upright, an arm extending from one end of said upright, said arm being provided with a slot and a recess, a second arm extending from the other end of said upright, a cam lever pivoted upon said second named arm, a plate slidably mounted on said upright and adapted to be engaged by said cam lever, a screw threaded pin depending from said slideable plate, and a screw threaded thimble in engagement with said pin and adapted to engage a valve rod, said first named arm being adapted to engage a 85 valve spring.

3. In a device of the character described, a rigid supporting frame, a laterally extending arm formed upon one end of said frame, a cam lever provided with a stop and pivoted upon said arm, a slidable plate mounted upon said frame and adapted to engage a valve rod, a second laterally extending arm formed upon the other end of said frame, | said second named arm being provided with a slot for receiving said valve rod and being adapted to engage a valve spring.
